UNITED STATES PATENT OFFICE.

ELISHA L. DAY, OF BRENHAM, TEXAS, ASSIGNOR OF ONE-HALF TO ROBERT E. GRAUL, OF SAME PLACE.

DESIGN FOR A SYRINGE NOZZLE-TIP.

SPECIFICATION forming part of Design No. 29,972, dated January 10, 1899.

Application filed December 19, 1898. Serial No. 699,772. Term of patent 14 years.

To all whom it may concern:

Be it known that I, ELISHA L. DAY, a citizen of the United States, residing at Brenham, in the county of Washington and State of 5 Texas, have invented and produced a new and original Design for a Syringe Nozzle-Tip, of which the following is a specification.

This invention relates to a new and original design for a syringe nozzle-tip; and it has for 10 its object to provide a design of this character which shall be both useful and ornamental.

The leading feature of the design resides in a tip-body having at one end a spheroidal head and a cylindrical stem extended from 15 one side of the head and provided with a plurality of spaced longitudinal grooves and a contracted annular neck-groove directly adjoining the head and having its annular side walls flared.

20 The minor features of the design are the cylindrical stem, having exterior threads between the neck-groove and one end thereof and also having its solid portion slightly tapered.

25 An additional minor feature of the design is the contracted annular neck-groove of the stem, having a flat annular base portion, from which the side walls of the groove flare outwardly.

30 In the drawings, Figure 1 is an elevation of

a syringe nozzle-tip embodying the herein-described design. Fig. 2 is a longitudinal section thereof. Fig. 3 is a cross-sectional view on the line 33 of Fig. 1. Fig. 4 is an end view of the tip.

35 Referring to the accompanying drawings, the numeral 1 designates the elongated tip-body, having at one end a spheroidal head 2 and having extended from one side of said head a cylindrical stem portion 3. The cylindrical stem portion 3 of the nozzle-tip is provided with a plurality of spaced longitudinal grooves 4 and with a contracted annular neck-groove 5 directly adjoining the head 2 and having a flat annular base 6 and beveled 40 side walls 7, which flare outwardly from said base 6. Between its contracted annular neck-groove 5 and one end thereof the said cylindrical stem 3 of the tip is provided with exterior threads 8.

45 50 What is claimed is—

The design for a syringe nozzle-tip herein shown and described.

In testimony that I claim the foregoing as my own I have hereto affixed my signature in 55 the presence of two witnesses.

ELISHA L. DAY.
